America, New York, N. Y., a corporation of
Delaware

Application October 31, 1934, Serial No. 750,794

2 Claims. (Cl. 178—7.5)

My invention relates to television systems, and particularly to systems in which cathode-ray tubes are employed at the transmitter and receiver.

5 In systems of this type it is especially desirable to obtain all voltages for the cathode-ray tube and the vacuum tubes at the receiver from an alternating current power line, such as a 60 cycle line. This requires that the alternating 10 current be stepped up to the desired voltage, rectified and filtered. It has been found that in a receiver where the voltage supply unit must be placed reasonably close to the cathode-ray tube there is an alternating current field surrounding this unit which extends to the cathode-ray tube and affects the deflection of the electron beam. In addition to this alternating current field which is superimposed upon the deflecting field of the cathode-ray tube, there is 15 an alternating current component in the output of the filter, because of imperfect filtering, which modulates the outputs of the deflecting circuits and which appears on the cathode-ray tube electrodes.

25 The effect of the alternating current field and alternating current hum component of the filter output, prior to my invention, was to impair or destroy the detail of the picture. An additional effect was a noticeable movement of the edge of 30 the picture. Shielding the voltage supply unit failed to eliminate the effect of the alternating current field while the alternating current component in the filter output could be reduced to a negligible value only by employing a filter so 35 expensive as to be prohibitive.

The alternating current field and the hum or ripple component in the filter output were found to be especially objectionable in a system employing the so-called "interlaced scanning". If 40 they were of sufficient magnitude they destroyed the "interlacing". In all cases they caused the scanning lines to "pair" with the result that the line structure of the picture became prominent. In addition to these effects, there were the previously mentioned effects tending to ruin the 45 picture.

At the transmitting station, also, it is desirable to obtain all unidirectional voltages from an alternating current supply. Just as in the 50 case of the receiver, prior to my invention any stray fields from the power supply which reached the cathode-ray transmitter tube caused a disturbance in the electron beam deflection such that interlacing and picture detail were adversely affected. Likewise, any hum or ripple voltage

which reached the deflecting circuit and cathode-ray tube caused a loss in picture detail.

Another difficulty was encountered prior to my invention whenever an attempt was made to use incandescent lamps lighted by alternating 5 current for illuminating a scene to be transmitted. That the light from such lamps varies in intensity is well understood, there being no visible flicker effect if 60 cycle current is used only because of the high frequency of the variation in light intensity. However, this variation in the light striking the mosaic of a transmitter tube causes an alternating current component to be superimposed upon the picture current with the result that the picture appearing at the receiver is unevenly lighted from top to bottom. This uneven brightness or shading of the picture could not be tolerated, largely because the shading did not remain stationary. Instead, the uneven shading drifted across the picture. Because 10 of this phenomenon, direct current lighting was utilized in television studios until my invention made it unnecessary.

An object of my invention is to provide a television system, and a method of operating the 20 same, in which the magnetic or electrostatic fields and the alternating current hum or ripple from power supply units will have substantially no detrimental effect upon the picture.

A further object of my invention is to provide 30 a television system employing "interlaced scanning" in which filtered direct current derived from an alternating current source may be utilized without impairing the interlacing.

A further object of my invention is to provide 35 a television receiver of moderate cost which may be operated from an alternating current power line.

A still further object of my invention is to provide an improved television transmitter in 40 which the effects of stray electric fields and of voltage ripples from an alternating current power supply are minimized.

It is a still further object of my invention to provide a television transmitter of the type utilizing a cathode-ray transmitter tube which will satisfactorily transmit a scene illuminated by incandescent lamps or the like lighted by alternating 45 current.

The above-described difficulties in obtaining a 50 good picture without the use of batteries in the transmitter and/or receiver were encountered, for example, in systems which employed a frame frequency of 48 pictures per second, the voltages being derived from a 60 cycle line. It had been 55

found that a frame frequency much lower than this caused flicker but that there appeared to be no reason for going to a frequency above 48 pictures per second as at this frequency there 5 was no flicker.

In accordance with the preferred embodiment of my invention I increase the frame frequency to the frequency of the power line; namely, to 60 pictures per second in the example being considered. As will appear from the following description, this is done in a system in which the synchronizing of the transmitter and receiver is accomplished by means of synchronizing impulses transmitted over the same channel as the picture signals. The result of changing the frame frequency to the same frequency as that of the power supply is that the magnetic and electrostatic fields and the alternating current ripple from the power supply unit no longer 10 affect the picture to any appreciable extent.

Other objects, features and advantages of my invention will appear from the following description taken in connection with the accompanying drawings in which

Figures 1 and 2 are circuit diagrams of a transmitter and a receiver, respectively, embodying my invention, and

Figs. 3 to 8 are diagrams which are referred to in explaining my invention.

Referring to Fig. 1, a television transmitter system is illustrated which includes a cathode-ray transmitter tube 1 of the type described in an article by Dr. V. K. Zworykin which appears in the January, 1934 issue of The Journal of the Franklin Institute. This tube comprises an evacuated envelope 3 having therein an electron gun consisting of a cathode 5, a control electrode 7, and a first anode 9, and a focusing and accelerating anode 11. The envelope 3 also includes 30 a mosaic 13 of light sensitive elements upon which is projected an image of the scene to be transmitted. Deflecting means, such as deflecting plates 15 and deflecting coils 17, are provided for deflecting the electron beam horizontally and vertically, respectively, in order to scan 35 the mosaic 13 with the electron beam.

An image of the object 19 to be transmitted is projected upon the mosaic 13 by means of a suitable optical system indicated at 21. If an 40 indoor scene is to be transmitted, it will usually be desirable to illuminate the scene by incandescent lamps, indicated at 23, which are lighted from the same 60 cycle power line 25 which supplies power to the transmitting system.

The electrodes of the transmitter tube 1 are supplied with unidirectional voltages of the proper value by means of a power supply unit connected to an alternating current supply which, in the example being described, is the 60 cycle 50 power line 25. The power supply unit is of conventional design and comprises a step-up transformer 27, a full wave rectifier 29 and a filter 31. The electrodes of the tube 1 are connected to suitable points on a voltage divider 33, which is connected across the output terminals of the filter 31.

To produce the desired saw-tooth current and saw-tooth voltage, for the deflecting coils 17 and deflecting plates 15, respectively, an electric discharge tube impulse generator is provided. This generator consists of a main oscillator 35 from 60 which are derived electrical impulses of the desired frequency for horizontal deflection and also electrical impulses of the desired frequency for 70 vertical deflection. The main oscillator 35 may

be a blocking oscillator consisting of an electrical discharge tube 37 having a cathode 39, a control grid 41 and an anode 43. The control grid 41 is connected through a variable grid leak resistor 45 and through a resistor 47 in the control circuit (which will be described hereinafter) to ground and through ground to the cathode 39.

The anode 43 is maintained at a positive potential by means of a suitable voltage source such as a battery 49 which has its negative terminal connected to the cathode 39 and its positive terminal connected through a resistor 51 and the primary winding 53 of a transformer 55 to the anode 43. A condenser 57 is connected in series with the secondary 59 of the transformer 55, the condenser 57 and secondary 59 being connected between the control grid 41 and the cathode 39.

The transformer windings 53 and 59 are so phased that an increase in plate current in the tube 37 causes the control grid 41 to become more positive whereby grid current flows into the grid condenser 57 to charge it in such a direction as to apply a negative bias to the control grid 41. The plate current finally approaches its saturation value so that its rate of increase becomes less, the voltage fed back to the grid decreases whereby the plate current decreases, thus reversing the phase of the voltage applied to the control grid 41 through the transformer 55 and biasing the tube 37 beyond cut-off. During the time the grid has been positive, the condenser 57 has been charged sufficiently to hold the tube biased beyond cut-off and no further oscillation takes place until the charge has leaked off the condenser 57 through the grid leak resistor 45 sufficiently to lower the grid voltage to a value which again permits flow of plate current.

The voltage impulses produced by the oscillator 35 are impressed upon a chain of frequency dividers 61, 63 and 65, each of which may be a blocking oscillator operating the same as the main oscillator 35 but at a lower frequency. Each oscillator is locked in step with the oscillation of next highest frequency.

The frequency of the main oscillator 35 is divided by the frequency divider chain in three steps of seven, as indicated on the drawings, to produce voltage impulses occurring at the rate of 60 per second, this being the frame frequency desired for practicing my invention in the specific example being described. The 60 cycle impulses are supplied to the input circuit of a saw-tooth wave generator or deflecting circuit 67 which converts them into voltage impulses of the necessary shape for causing a flow of current having a saw-tooth wave shape through the deflecting coils 17.

The horizontal deflecting impulses are obtained by impressing a portion of the output energy of the main oscillator 35 upon the input circuit of a frequency divider 69, such as another blocking oscillator, which divides the frequency of the main oscillator output by two to produce 10,290 60 impulses per second. The output of the frequency divider 69 is impressed upon a saw-tooth wave generator or deflecting circuit 71 which has its output connected across the horizontal deflecting plates 15 for impressing a saw-tooth 70 voltage thereon.

It will be noted that the vertical deflecting and horizontal deflecting frequencies are such as to cause 171½ lines per picture frame, in order to provide interlaced scanning as described and 75

claimed in application Serial No. 726,258, filed May 18, 1934, in the name of A. V. Bedford, and assigned to the Radio Corporation of America. Although my invention is described in connection with an interlaced scanning system, and is especially valuable in connection therewith, it should be understood that it is of general application.

A control circuit 73 is provided for maintaining the impulse generator locked in with the 60 cycle power line 25. The control circuit 73 includes an electric discharge tube 75 having a cathode 77, a control grid 79 and an anode 81. The tube 75 is so adjusted that it functions as a distorting amplifier or detector. In one specific embodiment this is accomplished by maintaining the control grid 79 at a high negative bias by means of a biasing source, such as a battery 83, the negative bias being high enough to bias the tube beyond the cut-off point. The anode 81 is maintained at a positive potential by means of a source of potential, such as a battery 85, having its negative terminal connected to the cathode 77 and its positive terminal connected to the anode 81 through the resistor 47. The resistor 47 is shunted by a filter condenser 87.

It will be noted that the resistor 47 is connected in series with the grid leak resistor 45 of the blocking oscillator 35 whereby any change in voltage drop across the resistor 47 causes a change in the bias on the control grid 41 of the blocking oscillator. The filter condenser 87 has sufficient capacity to integrate current impulses and cause a substantially steady flow of current through the resistor 47.

The current flow through the control circuit resistor 47 is caused to vary in response to any phase shift between the 60 cycle current from the power line 25 and the output of the frequency divider 65 by impressing the impulses from both the power line and the frequency divider upon the input circuit of the control tube 75.

The 60 cycle impulses appearing in the output circuit of the frequency divider 65 are impressed through a coupling condenser 89 and the secondary of a transformer 91 upon the control grid 79 of the tube 75. A 60 cycle voltage from the line 25 is also impressed upon the control grid 79 through the transformer 91 in such phase that it adds with the voltage impulses supplied by the frequency divider 65.

The effect of the control tube 75 and associated control circuit is to hold the output of the frequency divider 65 at the same frequency as the power line frequency and in a substantially fixed phase relation thereto. It will be understood that the frequency of the power line 25 is maintained substantially constant. However, slight frequency variations in the line frequency will occur and the control circuit 73 will cause the impulse generator to follow such frequency variations.

The above described control circuit is described and claimed in application Serial No. 729,730, filed June 9, 1934, in the name of A. V. Bedford, and assigned to the Radio Corporation of America.

During the transmission of a picture, the picture signals appear across a resistor 93 connected between the mosaic 13 and the second anode 11 and are impressed upon a picture signal amplifier 95 which amplifies them and impresses them upon a radio transmitter 97 or, if preferred, upon a transmission line (not shown).

In order to maintain the scanning at the re-

ceiver synchronized with the scanning at the transmitter, the vertical and horizontal synchronizing impulses are impressed through wave shaping amplifiers 99 and 101, respectively, and through an amplifier 94 upon a suitable point in the picture signal amplifier 95. When impressed upon the amplifier 94, the synchronizing impulses having the characteristics indicated by the curve 103, the horizontal synchronizing impulses being represented by the reference letter *x* and the vertical synchronizing impulses being represented by the reference letter *y*.

Referring specifically to the manner in which the square top impulses *x* and *y* are derived from the blocking oscillator outputs, the wave shaping amplifiers 99 and 101 may be resistance coupled amplifiers having successive vacuum tubes adjusted to "clip off" the lower and top portions of the wave impressed thereon. A wave shaping amplifier of this character is shown in the above-mentioned application Serial No. 729,730.

The vertical deflecting or framing impulse *y* is made wider than the horizontal deflecting impulses *x* by properly adjusting the blocking oscillators 65 and 69, respectively. The width of an impulse may be made the desired value by shunting the primary winding of the blocking oscillator transformer with a suitable amount of capacity, this capacity usually being distributed capacity. In general, also, the width of an impulse produced by the lower frequency oscillator tends to be greater than the width of an impulse produced by the higher frequency oscillator.

The amplifier 94 reverses the phase of the impulses *x* and *y*, as shown by the curve 103a, whereby they have a negative polarity. The synchronizing impulses may be mixed with the picture signals in the manner described and claimed in application Serial No. 653,976, filed January 28, 1933, in the name of R. L. Campbell, and assigned to the Radio Corporation of America. As described in the Campbell application, the negative synchronizing impulses are impressed upon an amplifier stage in the amplifier 95 where the polarity of the picture signals representing black is negative. This removes undesired transients or the like from the region of the picture signals so that they may be clipped or saturated off in a succeeding amplifier stage.

Referring to Fig. 2, the receiver comprises a cathode-ray tube 105 of the type employing electrostatic focusing. It consists of an evacuated envelope 107 having an electron gun at one end and a fluorescent screen 109 at the opposite end. The electron gun includes an indirectly heated cathode 111, a control electrode 113 and a first anode 115. A second anode 117 consisting of a silver coating on the inner surface of the envelope 107 is provided for aiding in the electrostatic focusing of the electron beam and for accelerating the electrons in the beam. The cathode-ray tube 105 is provided with deflecting coils 119 and 121 for deflecting the electron beam vertically and horizontally, respectively, whereby the fluorescent screen 109 is scanned by the electron beam to produce a picture.

The picture and synchronizing signals which have been radiated from the transmitter are received by a suitable radio receiver 123 and supplied to a picture amplifier 125. The signals impressed upon the picture amplifier are represented by the curve 120 where the synchronizing impulses are shown at *x* and *y*, and the picture signals at *z*. The signals appearing in the output circuit of the amplifier 125 are impressed through

a coupling condenser upon the control electrode 113 of the cathode-ray tube whereby the electron beam is modulated in accordance with the picture signals.

5 The picture and synchronizing signals are also impressed upon a separating circuit 127 in which the synchronizing signals are separated from the picture signals, and in which the horizontal synchronizing impulses are separated from the framing impulses. The vertical synchronizing or framing impulses are supplied to a suitable vertical deflecting circuit 129 which converts the synchronizing impulses into voltage impulses of the proper wave shape for causing a flow of saw-tooth current through the vertical deflecting coils 119.

15 The horizontal synchronizing impulses are supplied to a horizontal deflecting circuit 131 which converts them into voltage impulses of the proper wave shape for causing a flow of saw-tooth current through the horizontal deflecting coils 121. The horizontal and vertical deflecting circuits may be of any suitable design, such as the one illustrated as the horizontal deflecting circuit. This circuit, which is known as "a single tube 20 deflecting circuit", is described and claimed in application Serial No. 718,353, filed March 31, 1934, in the name of A. W. Vance, and assigned to the Radio Corporation of America.

25 The horizontal deflecting circuit comprises a vacuum tube 133 having a cathode 134, a control grid 135 and a plate 136. The plate 136 is connected to a suitable positive voltage supply through an inductance coil 137. The control grid 135 is connected through an inductance coil 139 30 to a point on a voltage divider 141 which is negative with respect to the cathode 134. The coils 137 and 139 are inductively coupled in such phase relation that an increase in plate current causes a voltage to be induced in the grid circuit which 35 drives the control grid 135 more positive. As described in the above-mentioned Vance application, this causes a saw-tooth current to appear in the plate circuit of the vacuum tube. By adjusting the natural period of oscillation of the tube 133 it may be made to produce saw-tooth 40 current impulses in synchronization with the horizontal synchronizing impulses which are impressed upon its control grid 135.

45 In the receiver illustrated, two voltage supply units are employed, one unit 143 for supplying the comparatively high voltages to be first and second anodes of the cathode-ray tube 105, and the other unit 145 for supplying the lower voltages to the deflecting circuits and other parts of 50 the television receiver.

55 The high voltage supply unit 143 comprises a step-up transformer 147, a double wave rectifier tube 149, and a filter 151. The first and second anodes of the cathode-ray tube 109 are connected 60 to suitable points on a voltage divider 153 which is connected across the output terminals of the filter 151, suitable by-pass condensers 154 and 155 being provided for the two anodes.

65 The voltage supply unit 145 comprises a step-up transformer 157, a double wave rectifier 159, and a filter 161. The plate 136 and control grid 135 of the vacuum tube 133 are connected to suitable points on the voltage divider 141 which is connected across the output terminals of the filter 161. The control grid of the cathode-ray 70 tube 105 also is connected through a resistor 163 to a point on the voltage divider 141 which is negative with respect to ground. Suitable by-pass condensers are provided for reducing to a 75 minimum the amount of 60 cycle hum which may

appear upon the grid and plate of the vacuum tube 133 and upon the control grid of the cathode-ray tube 105. The remaining units of the receiver, also, preferably are supplied with voltage from the power supply unit 145 as indicated by the conductors 158 and 160.

80 Preferably all the apparatus shown in Fig. 2 is installed in a single cabinet similar to the usual radio console, the power units 143 and 145 being located in the bottom of the cabinet and the cathode-ray tube 105 being located near the top of the cabinet. This places the power units so close to the tube 105 that it is practically impossible to prevent the stray field of the power units from influencing the deflection.

85 The two voltage supply units are supplied with alternating current from a 60 cycle power line 25a which preferably is the same power line as the one supplying power to the transmitter. If the same power line or power network supplies the transmitter and receiver, the picture appearing on the cathode-ray tube screen 109 will have no movement caused by any small hum or stray field in the receiver. If the transmitter and receiver are supplied from separate 60 cycle power 90 lines, there will be a very slow movement in the picture due to the stray field and hum, but, where the power line frequencies are held within close limits, this movement of the picture will be so slow that it will not be objectionable. In either case, 95 by making the frame frequency equal to the frequency of the power line an impairment of picture detail due to stray alternating current field and hum is avoided.

100 The effect of the ripple and stray field on a picture appearing at a receiver in a television system embodying my invention will be understood by referring to Figs. 3 to 7. Referring to Fig. 3, the large saw-tooth curve 165 represents both the vertical deflecting current and deflecting field 105 while the small saw-tooth curve 167 represents both the horizontal deflecting current and deflecting field. In order to simplify the drawing and aid in the construction of Fig. 4, the saw-tooth curve 165 has been given a much greater 110 amplitude than the saw-tooth curve 167 although the vertical and horizontal deflecting currents may have substantially the same amplitude. Also, only a small number of horizontal lines (10½) have been indicated for each picture frame 115 although, in the system illustrated in Fig. 1, the actual number of lines per picture frame is 171½. It will be understood that because of interlacing the apparent number of horizontal lines is double 120 the actual number of lines.

125 The stray field from a power supply unit is indicated by the sine wave curve 169. It is superimposed upon the vertical deflecting field to produce a resultant deflecting field indicated by the dotted line curve 171. It will be understood that the effect of the stray field has been greatly exaggerated in Fig. 3 in order to make its effect 130 more apparent. The effect of ripple in the voltage supply to the vertical deflecting circuit is the same as that of the stray field.

135 Fig. 4 represents the horizontal scanning lines for two successive picture frames as they appear on the fluorescent screen 109 of the cathode-ray receiver tube. The solid lines 173 represent the scanning lines produced during the first picture, 140 frame while the dotted lines 175 represent the scanning lines produced during the succeeding picture frame. The construction lines 176 and 177 indicate how Fig. 4 has been built up from the curves in Fig. 3.

An inspection of Fig. 4 will show that in spite of the large stray field component in the vertical deflecting field, the horizontal scanning lines of two successive pictures are perfectly interlaced, 5 the only effect of the hum being that in the middle of the picture the lines are crowded together somewhat, while at the bottom and at the top of the picture they are spread apart. In an actual picture, the crowding and spreading of the 10 lines are not noticeable.

It can readily be demonstrated that if the phase of the stray field component shifts appreciably with respect to the vertical deflecting field during the transmission of a picture, the interlacing of the picture will be destroyed either because of a "pairing" of the lines or because of the scanning lines of one picture frame being displaced by one or more lines with respect to those of the preceding picture frame. 15

It can also be shown that there must be an even number of half sine waves of the stray field component per picture frame in order to avoid destruction of the interlacing. In other words, the frame frequency should either be equal 20 to the power supply frequency or be a whole number sub-multiple thereof. For example, with a 60 cycle power supply, the frame frequency may be 30, 20, 15, or 10 pictures per second providing a system is employed which will reduce 25 flicker at these lower frequencies.

The effect of voltage ripple and stray field on the horizontal deflection will now be considered with reference to Figs. 5, 6 and 7. In Fig. 5, as in Fig. 3, the vertical deflecting current and field is represented by the saw-tooth curve 165 while the horizontal deflecting current and field is represented by the other saw-tooth curve 167. Also, the 60 cycle stray field and hum component is represented by the sine wave curve 169. The 30 stray field is superimposed upon the horizontal deflecting field to produce a resultant horizontal deflecting field indicated by the dotted saw-tooth curve 179.

The character of the picture produced by the 45 composite horizontal deflecting field is indicated at Fig. 6 where the lines 181 represent the scanning lines. It will be seen that the effect of the stray field is to cause a bend in the edges of the picture. It will be apparent from an inspection 50 of Fig. 5 that this bend in the picture edge is the same for each succeeding picture frame whereby the picture remains perfectly stationary so far as hum effects are concerned. In practice the bend in the edge of the picture is so slight 55 that it is hardly noticeable, due to the fact that the pattern remains stationary.

The horizontal deflection may be affected also by the 60 cycle hum modulating either the horizontal deflecting circuit or the electrodes of the 60 cathode-ray tube, or both. No curves have been shown to represent this modulated condition but it will be evident that the modulation will give the picture the characteristic indicated in Fig. 7 where the scanning lines are shown at 181. As 65 in the case of the superimposed field, the bend in the edge of the picture will remain constant for succeeding picture frames. It will be noticed that in Figs. 6 and 7, the effect of hum on the vertical deflection has been ignored.

Obviously there is an advantage in preventing a continuous movement of the edge of the picture as any such movement in itself would be objectionable. However, the greatest advantage in preventing this movement is that if only a slight 5 movement of the picture edge occurs, the picture detail is impaired. It is obvious that because of the very small size of a picture element, a very slight deflection of the electron beam produced by the hum or stray field would cause a blurring 10 of the picture.

While the effects of ripple and stray field have been described specifically with reference to the television receiver, the same effects are present at the transmitter even though it is feasible to 15 employ better filters and shielding there than at the receiver.

If alternating current lighting is employed for illuminating the scene to be transmitted, as indicated in Fig. 1 at 23, the picture at the receiver 20 is shaded substantially as shown in Fig. 8. My improved transmitter causes this shading pattern to remain stationary on the picture. The stationary shading pattern is far less objectionable than a shading pattern which is moving 25 across the picture. Furthermore, the stationary shading pattern can be corrected for, by means of a suitable circuit, to produce a picture of uniform shading.

In the claims, the reference to a "sub-multiple" 30 of a number includes the number itself.

It will be understood that various modifications may be made on my invention without departing from the spirit and scope thereof and I desire, therefore, that only such limitations shall be 35 placed thereon as are necessitated by the prior art and are set forth in the appended claims.

I claim as my invention:

1. The method of operating a television system of the type comprising a receiver adapted to be 40 energized from an alternating current power line, the receiver including a cathode ray tube on an element of which the received picture appears, which comprises deriving unidirectional potentials from said power line, supplying said potentials to said receiver, distantly producing and transmitting picture and synchronizing signals, intercepting said signals and supplying them to the receiver, and supplying to the receiver framing impulses recurring at substantially the same 45 frequency as that of the said power line.

2. The method of operating a television system of the type comprising a receiver adapted to be energized from an alternating current power line, the receiver including a cathode ray tube on an 50 element of which the received picture appears, which comprises deriving unidirectional potentials from said power line, supplying said potentials to said receiver, distantly producing and transmitting picture and synchronizing signals, intercepting said signals and supplying them to the receiver, and supplying to the receiver framing impulses recurring at a frequency substantially the same as that of a sub-harmonic of the 55 frequency of the said power line.

65

WILLIAM A. TOLSON.
